UNITED STATES PATENT OFFICE.

CHARLES W. SNOOK, OF NEW YORK, N. Y.

DESIGN FOR A CALENDAR.

SPECIFICATION forming part of Design No. 17,379, dated June 7, 1887.

Application filed May 2, 1887. Serial No. 236,886. Term of patent 7 years.

To all whom it may concern:

Be it known that I, CHARLES W. SNOOK, a citizen of the United States, residing in New York, county and State of New York, have 5 invented and produced a new and original Design for Calendars, of which the following is a specification, reference being had to the accompanying drawings.

Figure 1 is a face view of my newly designed calendar. Fig. 2 is a vertical central section thereof.

The leading feature of this design consists of an animal's face having a protruding convex tongue, which is slotted.

a is an animal's face having an open mouth, 15
b, through which protrudes a convex tongue, *c*.
This tongue is slotted, as shown.

What I claim is—

The design for a calendar, consisting of face
a, having open mouth *b*, and convex, protrud- 20
ing, slotted tongue *c*, substantially as shown.

CHARLES W. SNOOK.
